UNITED STATES PATENT OFFICE.

GEORGE P. BOSWORTH, OF CENTRAL FALLS, RHODE ISLAND, ASSIGNOR TO HEMPHILL COMPANY, OF CENTRAL FALLS, RHODE ISLAND, A CORPORATION OF MASSACHUSETTS.

YARN OR THREAD FEEDING MECHANISM FOR SPRING-NEEDLE MACHINES.

Application filed July 28, 1922. Serial No. 578,103.

This invention relates to yarn or thread feeding mechanism for circular knitting machines preferably of the spring needle type. In order that the principle of the invention 5 may be readily understood, I have disclosed a single embodiment thereof in the accompanying drawings, wherein—

Fig. 1 is a plan view of a spring needle circular hosiery machine having my invention applied thereto;

Fig. 2 is a side elevation of the construction shown in Fig. 1;

Fig. 3 is a detail upon a larger scale in side elevation of one of the yarn feeding fingers and indicating the mounting thereof and its functioning and non-functioning positions; and

Fig. 4 is a slightly modified form of yarn finger.

While not restricted thereto, my invention is particularly applicable to machines having needles of other than the pivoted latch type. I have illustrated my invention as applied to a spring needle split-foot 25 hosiery machine.

The machine to which my invention is represented as applied is in its general character of the well known Banner type having a rotary needle cylinder 1 and a stationary cam ring, the support whereof is indicated generally at 2, the block for the main knitting cams being indicated at 3 and that for the opposed, suture or seam creating cams being indicated at 4. The 30 machine being represented as of the spring beard needle type, it is provided with a member or partial ring 5 pivoted at 6 so as to be swung up out of functioning position for any purpose. Said ring as illustrated occupies substantially a half circle and I have represented a latch lever 7 pivoted at 8 upon the supporting standard 9 for the partial ring 5 and adapted to engage a pin 10 to hold the said partial ring 5 in functioning position. At one side of the knitting head, namely, at the right hand side viewing Figs. 1 and 2, I provide desirably a plurality of yarn or thread guides indicated at 11, 12, 13, 14, 15, each of the character to be described, and at the opposite side I provide preferably a single yarn or thread guide 16 of the same character. All of said 45 yarn guides are adapted to be lifted out of action and to be depressed into action in

any suitable manner not herein necessary 55 fully to describe. Desirably those at the right hand side of the knitting head viewing Figs. 1 and 2 are elevated out of action and lowered into action by means similar to those disclosed in the patent to Joshua D. Hemphill, No. 933,443. The yarn guide 16 at the opposite side of the knitting head may be lifted out of action by suitable means including if desired a lever 17 pivoted at 18 upon a suitable standard 19 and adapted to be 60 moved by the parts 20, 21 at proper times.

The spring beard needles herein indicated are or may be of the usual spring beard type as for example those shown in the patent to George P. Bosworth, No. 1,235,545, and to 70 that end they are independently reciprocated in their grooves and independent pressers are provided to close their beards at the proper times. Desirably web holders are employed of any suitable character not herein shown. It is necessary in feeding the yarn or thread to spring beard needles to supply the same thereto at a relatively low point, lower than with latch needles, and it is also important that the yarn or thread 75 guide at its feeding position be close to the needles. If, however, the yarn guide or guides be pivoted in the ordinary manner so as to swing up and down upon a fixed pivot, they will not when in their lowermost 80 position be near enough to the needles satisfactorily to supply the yarn thereto, and if on the other hand the yarn guide or guides be so mounted upon a fixed pivot that when in their lowermost position, they are close 85 to the needles, in being lifted into inoperative position they strike the needles and prevent proper operation thereof and cannot 90 themselves function. In order to meet these and other difficulties, I have provided the 95 following arrangement of parts.

At the left hand end of the partial ring 5 viewing Figs. 1 and 2, I have secured a plate 23 having a vertical face and thereon I fix a protruding pivotal pin 24 for the 100 yarn or thread guide 16 and a protruding guiding pin 25. At the opposite side of the partial ring 5 I provide a similar construction, though omitting if desired a plate corresponding to the plate 23. I provide at 105 that side of the machine a pivotal pin 26 and the pin 10 for guiding the up and down movements of the yarn guides or fingers.

The yarn guide 16 is provided with a slot 27 which is parallel with the sides or edges 28, 29 of the yarn guide 16 and wherein is received the pivotal pin 24. The yarn guide 16 is provided with a curved slot 30 of the form shown, extending generally transversely thereof and receiving the pin 25 and in cooperation with the pin 24 compelling the yarn guide 16 in its rising and falling movements to partake of an in and out movement of such a character that when the said yarn guide is in the depressed position indicated in full lines in Figs. 2 and 3, the inner end of such yarn guide is close to the shanks of the needles and at its lower end where the thread is fed therefrom, is below the points of the beards so that said thread guide may properly lay the yarn or threads against the shanks of the needles. As the yarn guide 16 is elevated it is moved slightly outward in the general direction of its length through the influence of the curved slot 30 and so as to miss the beards of the active needles indicated at 31 and then is moved inward again into the dotted line position when above the idle needles indicated at 32, such movements occurring automatically through the cooperation of the pins 24, 25 and the slots 27, 30.

30 The yarn guide 16 is provided with a set screw 33 and a locking screw 34 therefor, the former being adapted to engage the pin 25 in any adjusted position and thus to control the extent of movement of the said 35 yarn guide as it in effect determines the effective length of the curved slot 30.

Viewing Figs. 2 and 3, it will be observed that when the yarn guide 16 is elevated into inactive position, it is substantially directly over the idle needles 32 so that the idle yarn leading therefrom to the usual clamp at the inside of the needle circle cannot be engaged by the idle needles, as would be the case were the former constructions employed to 45 which I have referred. When the yarn guide 16 is moved downward into functioning position again, the described in and out movement is reversed. The construction of the yarn guides 11 to 15 at the opposite side 50 of the machine is substantially the same, and the movements thereof are similar so far as the up and down and in and out movements are concerned, and therefore need not be more fully described, it being merely noted that a curved slot 30 is provided in each of said yarn guides and also a set screw 36 and a locking screw 37 therefor.

I have provided a coiled spring 38 connected to the yarn guide 16 and to some 60 fixed part of the machine, tending to move said yarn guide down into action or to hold it in action, and a similar spring 39 for each of the yarn guides 11 to 15. If desired, and as shown I may provide the inner end 65 of each yarn guide 11 to 16 with a tube 39'

of less diameter than the end of the guide and having a notch 40 leading to the passage through the tube and receiving the yarn. This construction is desirable as the small diameter of the tubes permits the feeding ends thereof to extend into exact feeding position. In Fig. 4 I have shown a curved tube 41 for the same purpose.

Having thus described one embodiment of my invention, I desire it to be understood that although specific terms are employed, they are used in a generic and descriptive sense and not for purposes of limitation, the scope of the invention being set forth in the following claims.

Claims—

1. A spring beard needle knitting machine having a rotatable needle cylinder with a circular series of needles, a partial ring transversely positioned at the upper end of said cylinder and terminating in opposed end upright faces for the reception of yarn guides and having at least at one of said faces one or more yarn guides adapted to be moved into elevated, non-functioning position with their inner ends wholly above inactive needles and into lower functioning position, a pivotal pin or pins for said yarn guide or guides, the latter being slotted to afford slight sliding movement upon said pin or pins, said guide or guides each having a curved slot and a pin positioned in said slot to guide the movement of the respective yarn guide, said slots and pins being so relatively positioned that when each yarn guide is down in functioning position, it is close to the shanks of the active needles below the beards at the yarn feeding point, and when in elevated inactive position is substantially directly over the path of the needles and above the highest point of elevation of the idle needles, so that the inactive yarns leading to the yarn clamp are not engaged by the idle needles.

2. A spring beard needle knitting machine having a rotatable needle cylinder with a circular series of needles, a partial ring transversely positioned at the upper end of said cylinder and terminating in opposed end upright faces for the reception of yarn guides and having each of said upright faces provided with two protruding pins, a yarn guide at each said face having a longitudinally extending slot near its rear end and wherein said pivotal pin is received, said yarn guides each having an inclined transversely extending slot wherein the other pin is received, whereby in the up and down movements of the yarn guide it is positioned for feeding below the yarn receiving portions of the needles at its feeding point and when elevated is substantially directly above the path of the needles and out of the way of the idle needles the inner end of said yarn guide being so shaped that in its

said elevated position it is wholly above the idle needles.

3. A spring beard needle knitting machine having a rotatable needle cylinder with a circular series of needles, a partial ring transversely positioned at the upper end of said cylinder and terminating in opposed end upright faces for the reception of yarn guides and having each of said upright faces provided with two protruding pins, a yarn guide at each said face having a longitudinally extending slot near its rear end and wherein said pivotal pin is received, said yarn guides each having a slot transversely extending and eccentrically positioned with regard to the pivot of said yarn guide, and in which slot the other pin is received, whereby in the up and down movements of the yarn guide it is positioned for feeding below the yarn receiving portions of the needles at its feeding point and when elevated is substantially directly above the path of the needles and out of the way of the idle needles.

4. A spring-beard needle, circular, knitting machine having a rotatable needle cylinder with a circular series of independent needles, a substantially semi-circular ring transversely positioned at the upper end of said cylinder and terminating substantially at the yarn feeding points in opposed end upright faces for the reception of yarn guides, and having at each of said upright faces a movable yarn guide, each of said yarn guides having a longitudinally extending slot for the reception of a pivotal pin upon one of said upright faces of the partial ring, and an inclined transversely extending slot for the reception of a second pin also in each case provided upon the adjacent upright face of the partial ring, whereby each yarn guide receives a pivotal up and down movement upon its pivotal pin, so as to feed the yarn to the spring-beard needles close thereto, and whereby when the yarn guide is elevated, it is substantially directed above the path of the needles and out of the way of the idle needles.

5. A spring-beard needle, circular, knitting machine having a rotatable needle cylinder with a circular series of independent needles, a substantially semi-circular ring transversely positioned at the upper end of said cylinder and terminating substantially at the yarn feeding points in opposed end upright faces, for the reception of yarn guides and having at each of said upright faces a movable yarn guide, each of said yarn guides having a longitudinally extending slot for the reception of a pivotal pin upon one of said upright faces of the partial ring, and a transversely extending slot eccentrically positioned with respect to the pivot of the yarn guide, one of said pins being received as a pivotal pin in the longi-

tudinally extending slot and the other of said pins being received in the transversely extending, eccentrically positioned slot, whereby each yarn guide has a pivotal up and down movement, and in its downward position is adapted for feeding close to the spring beard needles and when elevated is substantially directly above the path of the needles and out of the way of the idle needles.

6. A circular knitting machine having a rotatable needle cylinder with a circular spring beard series of needles, a partial ring having two substantially vertical faces at substantially 180° apart, each of said faces being provided with two protruding pins, a yarn guide at each face having a longitudinally extending slot near its rear end and wherein its pivotal pin is received, each yarn guide also having a curved, transversely extending slot wherein the other pin therefor is received, whereby in the up and down movements of the yarn guides each is positioned for feeding close to the needles at its feeding point and when elevated is substantially directly above the path of the needles and out of the way of the idle needles.

7. A circular, spring beard needle, knitting machine having a rotatable needle cylinder with a circular series of spring beard needles, a partial ring having two substantially vertical faces at substantially 180° apart, each of said faces having two protruding pins, a yarn guide for each face and having a longitudinally extending slot near the rear end thereof for the reception of its pivotal pin, each yarn guide having an inclined, transversely extending slot wherein its other pin is received, whereby in the up and down movement of each yarn guide it is positioned for feeding below the beards of the needles at its feeding point and when elevated is substantially directly above the path of the needles and out of the way of the idle needles.

8. A spring-beard needle, circular, knitting machine having a rotatable needle cylinder with a circular series of independent needles, a substantially semi-circular ring transversely positioned at the upper end of said cylinder and terminating substantially at the yarn feeding points in opposed end upright faces for the reception of yarn guides and having at each of said upright faces a movable yarn guide, each upright face being provided with two protruding pins, each yarn guide having a longitudinally extending slot near its rear end, and wherein one of said pins is received as a pivotal pin, each said yarn guide also having an inclined, transversely extending slot, wherein the other said pin is received, whereby in the up and down movements of each yarn guide it is positioned for feeding

- below the yarn receiving portions of the spring beard needles at its feeding point, and when elevated is substantially directly above the path of the needles and out of the way of the idle needles, the inner end of each yarn guide being so shaped that in its elevated position it is wholly above the idle needles.
9. A spring beard, independent needle, circular, knitting machine having a rotatable needle cylinder with a circular series of such needles, a substantially semicircular ring transversely positioned at the upper end of said cylinder and pivoted so as to be turned up out of action, said ring terminating substantially at the yarn feeding points in opposed vertical end faces for the reception flatwise thereagainst of a yarn guide, each of said vertical faces being provided with two horizontally protruding pins having free outer ends, each said yarn guide having close to its outer end a longitudinally extending slot, and wherein one of said pins is received as a pivot, said slot being of materially greater length than the diameter of said pin, each said yarn guide having substantially wholly below said pivotal pin an inclined transversely extending slot wherein said other pin is received, whereby in the up and down movements of each of said yarn guides such guide is positioned for feeding below the yarn receiving portions of the spring beard needles close to the stems of the said needles, and when elevated is substantially directly above the vertical path of the said needles and out of the way

of the idle needles, each yarn guide having at its feeding end a tube of reduced diameter.

10. A spring beard, independent needle, 40 circular, knitting machine having a rotatable needle cylinder; a substantially semicircular ring transversely positioned at the upper end of said cylinder and terminating substantially at the yarn feeding points in 45 opposed vertical faces for the reception of yarn guides and having at each of said vertical faces a movable yarn guide, each said yarn guide having near its outer end a longitudinal slot, a pin extending from the corresponding vertical face and passing through said slot, each said yarn guide having an inclined transversely extending slot between its inner and outer ends and a second pin extending from the corresponding face and received within said inclined slot, said second pin being located substantially lower than the first pin, whereby when each yarn guide is in feeding position, it is supported in a downwardly inclined position with said second pin at the upper end of the inclined slot, and the pivotal pin at the outer end of the first mentioned slot, and whereby, when each yarn guide is lifted into inoperative position, the upper end of said inclined slot remains below the level of the said pivotal pin, thereby limiting the upward movement of each yarn guide.

In testimony whereof, I have signed my name to this specification.

GEORGE P. BOSWORTH.
